UNITED STATES PATENT OFFICE.

PAUL M. HOTCHKIN, OF CHICAGO, ILLINOIS, ASSIGNOR TO NATIONAL X-RAY
REFLECTOR COMPANY, OF CHICAGO, ILLINOIS, A CORPORATION OF ILLINOIS.

DESIGN FOR A LAMP-REFLECTOR.

47,136.

Specification for Design.

Patented Mar. 23, 1915.

Application filed December 8, 1913. Serial No. 805,467. Term of patent 7 years.

To all whom it may concern:

Be it known that I, PAUL M. HOTCHKIN, a citizen of the United States, residing at Chicago, in the county of Cook and State of Illinois, have invented a new, original, and ornamental Design for Lamp-Reflectors, of which the following is a specification, reference being had to the accompanying drawing, forming part thereof.

The figure is a side elevation, showing my new design.

Referring to the drawing it will be seen that my design comprises an integral body consisting of two superimposed gracefully formed conical members joined together at their apices to form a hollow hour-glass shaped reflector. The upper member is an inverted cone, the base of which is flat and an intermediate portion of the side wall is a true cone,—that is, the contour comprises straight converging lines, the juncture with the base being formed by curving the wall inwardly very slightly to meet the line of the base. The neck formed by the meeting

of the two cones is concave, the widest diameter of which is slightly less than the diameter of the adjacent portion of the upper cone with which it merges through an upwardly and outwardly curved convex wall. The lower portion of the base of the bottom member has its walls of cylindrical shape parallel with each other and from the upper portion of this cylindrical base the walls are convex by curving them upwardly and inwardly in a long graceful curve to meet the wall of the neck portion with which it merges from a compound curve. Thus it will be seen that the contour of the reflector is made up of a plurality of graceful compound curves meeting each other and forming a reflector of esthetic appearance.

I claim,—

The ornamental design for a lamp reflector, as shown and described.

PAUL M. HOTCHKIN.
